UNITED STATES PATENT OFFICE.

THOMAS B. COSLEY, OF NEW YORK, N. Y.

HAND-STAMP PRINTING-PRESS.

SPECIFICATION forming part of Letters Patent No. 276,779, dated May 1, 1883.

Application filed June 10, 1882. (No model.)

To all whom it may concern:

Be it known that I, THOMAS B. COSLEY, of the city, county, and State of New York, have invented a new and Improved Hand-Stamp 5 Printing-Press, of which the following is a full, clear, and exact description.

The object of my invention is to provide a new and improved device for facilitating the printing of cards, bill-heads, envelope-headings, and like matter by means of a hand-stamp.

Reference is to be had to the accompanying drawings, forming part of this specification, in which similar letters of reference indicate corresponding parts in both the figures.

15 Figure 1 is a plan view of my improved hand-stamp printing-press. Fig. 2 is a longitudinal sectional elevation of the same on line *xx*, Fig. 1.

The base-board A is provided with a raised 20 edge or frame, B, which is removed or does not project above this base at the front end. At its rear end this base-board is provided with a large recess, C, for receiving the inking cushion or pad D, of the usual construction, which cushion or pad can easily be removed. A sliding board, E, fitting between the sides of the frame of the base-board A, is provided at its front end and on its upper surface with a handle or knob, F, and at its rear 25 or inner end with a raised plate, G. At its rear or inner surface it is provided in its upper surface with a series of longitudinal grooves, *a*, at each side, for receiving gage-strips H, which are placed a greater or less distance 30 apart, according to the width of the sheets I, cards, envelopes, &c., to be printed. A curved rod or strip, J, projects downward from the handle-knob toward the inner end of the sliding board E, and on this curved strip the ends 35 of the sheets I rest. The purpose of the strips J is to make the edge of each sheet project somewhat beyond that of the sheet below to withdraw it after it has been printed upon.

A piece of felt, K, cloth, leather, or like material, is attached to the under surface of the sliding board E, at the inner end, and serves as an ink-distributer. A curved arm, L, projects from the rear of the base-board A in such a manner that its upper end will be above the 45 middle of the pad or cushion D. A spring stamp-handle, M, is held to move vertically in the end of the arm L, and to the lower end of

this handle a plate, N, is attached. The type-block O is provided on its upper surface with two transverse plates or strips, P, having the 55 adjoining edges raised. The edges of the plate N are passed under the raised edges of the strips or plates P, whereby the type-block will be held to the plate N. The type-plate Q can be made of rubber or metal, as may be desired. 60 A support, R, is provided on the inner surface of the rear end of the frame B for the rear or inner end of the sliding board E while the impression is being made.

The operation is as follows: The sheets, I, to 65 be printed are placed on the sliding board E between the gage-strips H, which are adjusted according to the width of the sheets or cards or other matter. The sliding board E is withdrawn in inverse direction of the arrow *a'*. 70 The type-plate Q is pressed down on the inking-cushion D to be inked, and the spring in the handle M raises it. The sliding board E is pushed back in the direction of the arrow *a'*, so that the sheets will be under the type-plate, 75 which is then pressed on the sheets and makes the impression. The board E is withdrawn, the printed sheet is removed, the type-plate is again inked, the board E is pushed back, an impression is made, and so on. When the im- 80 pression is made the inner or rear end of the sliding board E has a firm bearing on the support R, as shown in dotted lines in Fig. 2. Every time piece of felt or cloth K passes over the cushion D it distributes the ink on the 85 same and supplies it with fresh ink. The type-block O and the inking pad or cushion D can easily be removed and replaced by others. The type-plate will always make a true and even impression, as all sheets are successively 90 placed in the same place under the type-plate. The sliding board E keeps the ink-cushion covered, and thus protects it drying out and from dust, &c.

Having thus described my invention, I claim 95 as new and desire to secure by Letters Patent—

1. The combination, with a base-board, a hand-stamp, and an inking-pad, of a sliding sheet-carrier and an ink-distributer, consisting of a piece of cloth, felt, or like material attached to the under side of the sliding sheet-carrier, substantially as herein shown and described, and for the purpose set forth.

2. The combination, with the base-board A,

the inking-pad D, and the hand-stamp L M O, of the support R at the end of the base-board A, substantially as herein shown and described, and for the purpose set forth.

5 3. The combination, with an inking-pad and a hand-stamp, of the sliding sheet-carrier E, the handle or knob F, and the curved strip or

wire J, substantially as herein shown and described, and for the purpose set forth.

THOS. B. COSLEY.
